UNITED STATES PATENT OFFICE.

WILLIAM W. MITCHELL AND HENDERSON W. COTTER, OF CANTON, NORTH CAROLINA.

FIRE-ALARM.

1,081,855.

Specification of Letters Patent. Patented Dec. 16, 1913.

Application filed April 29, 1913. Serial No. 764,422.

To all whom it may concern:

Be it known that we, WILLIAM W. MITCHELL and HENDERSON W. COTTER, citizens of the United States, residing at Canton, in the county of Haywood and State of North Carolina, have invented new and useful Improvements in Fire-Alarms, of which the following is a specification.

This invention is an improved fire alarm apparatus for automatically sounding an alarm at a building in the event that a fire occurs in any part thereof and for also closing an electric circuit so as to turn in a fire alarm at a fire department or other point connected with the alarm apparatus, the object of the invention being to provide an apparatus of this class which is cheap and simple, which may be readily installed and which is efficient and automatic in its operation, the invention consisting in the construction, combination and arrangement of devices hereinafter described and claimed.

In the accompanying drawings:—Figure 1 is a side elevation of a fire alarm apparatus constructed in accordance with our invention, showing the various operating cords extending to within portions of the building. Fig. 2 is a plan of the same. Fig. 3 is a transverse sectional view of part of the same. Fig. 4 is also a transverse sectional view of the same on a different plane from that of Fig. 3. Fig. 5 is a detail elevation of the gears which connect the power shaft and the counter shaft. Fig. 6 is a detail elevation of the holding lever and the tappet arm of the counter shaft, the counter shaft being shown in section.

In accordance with our invention, we provide a suitable base 1 at one end of which is a pair of vertical standards 2 which have bearings at their upper ends for a rock shaft 3 which has an arched portion 4 at its center and is provided at one end with a crank 5.

45 A bell 6 is suspended from and attached to the center of the arched portion of the rock shaft and is provided with a swinging clapper 7. A shaft 8 also has its bearings in the standards, is provided at one end with a hand crank 9 and also has a suitable drum 10 and a spur gear 11. The gear 11 engages a smaller gear 12 on one end of a countershaft 13, the countershaft being provided with a crank 14 the wrist 15 of which 50 is spaced from the countershaft a considerably less distance than the length of the

crank 5 of the rock shaft 3. A rod 16 connects the wrists of the cranks 14 and 5 and owing to the fact that the radius of the crank 14 is considerably less than that of the crank 5, the shaft 3 will be caused to rock or oscillate so as to swing and ring the bell when the shaft 13 is rotated.

The gear 11 is loose on the shaft 8 and is connected thereto by a suitable pawl and ratchet connection indicated at 17—18 which permits the shaft 8 to be turned in one direction without revolving the gear 11 and to wind up the cord 19 on the drum, one end of the cord being attached to the drum, the cord being passed over a suitable pulley 20 and a suitable weight 21 being attached to the pendant end of the cord, the weight serving to set the bell swinging apparatus in operation when the shaft 13 is released by the means and in the manner hereinafter described. The said shaft 13 has a tappet arm 22 here shown as projecting radially therefrom. A holding lever 23 is fulcrumed as at 24 on a suitable support 25 which rises from the base 1. The shorter end of the holding lever is normally engaged with the tappet 22 of the shaft 13 so that the said holding lever is normally held in elevated, horizontal position, by the engagement of the tappet therewith.

At the outer end of the holding lever, on its under side, is a hammer or stud 26 arranged to engage the movable member 27 of an electric circuit closer 28, when the holding lever drops, so as to cause the holding lever to close an electric circuit, the conductors of which are indicated at 29 and lead to a suitable alarm apparatus at a fire department or at any other suitable point distant from the building in which our alarm apparatus is installed.

Arranged over and transversely of the holding lever are a series of drop arms 30 each of which is pivotally connected as at 31 to a suitable support 32 that rises from the base 1. These drop arms are normally held in raised position, above the holding lever and prevented from bearing thereon by suitable cords 33 which run over pulleys 34 and lead to different rooms or portions of the building, each of the cords being attached at one end in a room or some locality in a building and the cords being held under tension by the weight of the drop arms and also by means of weights 35 which are shown as connected to the drop arms and suspended

therefrom. These cords may be either inflammable throughout their entire length or provided at suitable points with inflammable or easily combustible portions. In the 5 event of a fire in any part of the building to which one of the cords lead, the cord is consumed and breaks, thereby releasing the drop arm and the weight to which it is connected and, hence, the drop arm drops upon 10 the holding lever, the inner end of the latter is disengaged from the tappet 22 thus starting our local fire alarm apparatus in operation and as the stud 26 of the holding lever closes the circuit at 27—28, an electric alarm 15 is also turned in at the distant point to which the conductors 29 lead, thus also sounding an alarm at the fire department.

While we have herein shown and described a preferred form of our invention, 20 we would have it understood that changes may be made in the form, proportion and construction of the several parts without departing from the spirit of the invention and within the scope of the appended claim.

25 We claim:—

Alarm apparatus of the class described comprising a rock shaft having a crank and

a bell carried and adapted to be swung by the rock shaft, a power shaft, means to turn the power shaft, a countershaft geared to 30 the power shaft and having a crank of less radius than that of the rock shaft and also provided with a tappet, a rod connecting the wrists of the said cranks of the countershaft and rock shafts, a holding lever 35 pivotally mounted and with one arm normally engaged and held in elevated position by the tappet of the countershaft, one or more drop arms arranged above the other arm of said lever and adapted to drop thereon, and a cord leading from each drop arm to a distant point and including a combustible portion, the said cord being normally 40 under tension by the weight of the drop arm and serving to normally hold the latter 45 above the holding lever.

In testimony whereof we affix our signatures in presence of two witnesses.

WILLIAM W. MITCHELL.
HENDERSON W. COTTER.
